UNITED STATES PATENT OFFICE.

ABRAHAM J. SCHANTZ, OF ORRVILLE, OHIO.

SHAFT-PACKING.

Specification of Letters Patent. Patented Sept. 17, 1918.

1,279,452.

Application filed November 12, 1917. Serial No. 201,711.

To all whom it may concern:

Be it known that I, ABRAHAM J. SCHANTZ, a citizen of the United States, residing at Orrville, in the county of Wayne and State of Ohio, have invented a new and useful Shaft-Packings, of which the following is a specification.

The present invention relates to organ blowers and has for its object to provide a blower, especially adapted for use on organs located in churches or like places where it is especially desirable to muffle any noise created by the blower.

Another object is to construct a blower that is simple to install and having the air intake section hingedly connected to the fan casing for the purpose of giving access to the fan casing.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

In the accompanying drawings:

Fig. 1 is a longitudinal section through my fan blower, showing the motor connected therewith.

Fig. 2 is an end elevation illustrating the manner in which I hinge the air intake section.

Fig. 3 is a section taken on the line 3—3, of Fig. 1, looking in the direction of the arrow.

Fig. 4 is an enlarged sectional view of the improved packing which I use on the drive shaft at the point where it enters the fan casing.

Fig. 5 is a perspective view of the same with the suspension means removed.

Fig. 6 is a view illustrating a blank which I use in forming the metal part of my packing member.

Similar numerals of reference indicate corresponding parts throughout the several figures of the drawings.

In general my organ blower is constructed in accordance with Patent No. 1,117,605, which was issued Nov. 17, 1914. The base frame member 1, the motor 2 and fan motor shaft 3 and fans 4 are all of similar construction to that illustrated in my patent above referred to. The casing in which are mounted the fans I now construct in the form of a cylindrical drum having a straight wall 5 on the side next to the motor and a substantially conical wall 6 upon the opposite side, a bracket 7 fixed to the conical wall 6 supports the bearing 8, for the end opposite the motor, of the drive shaft 3.

As shown in Fig. 2 I construct my air intake compartment in the form of a cylinder generally indicated at 10, which fits snugly over a collar 11 projecting from the end wall 6 of the fan casing. An opening 12 in the outside end of the air intake is provided to admit the air to be sucked through into the fan casing and the said opening is covered with a fine mesh wire screen or other suitable material for preventing dust from being carried into the fan and being blown up through the organ pipes. Within the casing 10 I have, as clearly shown in Fig. 1, a series of annular spaced plates 13 with central openings therein, the object of these plates being to form a muffling device to drown any noise created by the air as it is sucked into the fan casing. Lugs 14 are provided on the end wall of the fan casing adapted to register with similar lugs 15 formed on the casing 10 and a pin 16 passed through openings in the said lugs forms a hinge joint which permits the casing 10 to be swung outwardly to permit access to the fan casing for the purpose of lubricating the shaft or making any adjustments from time to time that may be necessary to the fan blades, etc. Upon the opposite side of the casing 10 from that on which the hinges are located I provide a pin 17 which is adapted to engage a spring pressed locking member 18 carried by the fan casing. In this way the casing 10 can be closed tightly upon the flange 11 and locked in engagement therewith to form an air tight joint.

In the end wall 5 of the fan casing I provide an aperture 20 to admit the drive shaft 3 to the said fan casing. This aperture is

of larger diameter than the shaft 3 for the purpose of allowing adjustment of the fan blades with relation to the motor and I, therefore, provide a packing member to 5 form an air tight joint around the said shaft 3 to prevent the escape of air from the fan casing through the aperture 20. This packing member consists of a sheet metal plate 21, substantially square in blank form and 10 with a depending portion 22 clearly shown in Fig. 6. Upon the inner face of the sheet metal plate I place a square of leather 23 which is slightly smaller in dimensions than the metal plate. The corners of the plate 15 are then bent at an angle of 45° to its edges as indicated by the dotted lines in Fig. 6 and clearly shown in the perspective view. These inturned corners 24 are pressed down upon the face of the leather member and 20 the points thereof are then turned in as shown at 25 and serve to secure the leather member upon the plate 21. The bottom depending portion 22 is then turned up and the joints 26 between said portion and the 25 adjoining portions 24 is soldered to form a "water tight" joint. This forms a well clearly shown in Fig. 4 and indicated at 27 for the purpose to be hereinafter pointed out. A central opening 28 formed in the 30 leather portion is adapted to fit snugly about the drive shaft 3, thereby forming an air tight packing. Upon the opposite side of the metal plate 21 is cemented or secured in other suitable manner a piece of felt 29 35 conforming in outline with the plate 21 after the corners thereof have been turned down. A frusto-conical flange is formed upon the plate 21 having a central opening 30 which registers with the opening 28 40 formed in the leather portion. An opening 31 is also formed in the felt portion and fits about the frusto-conical flange on the plate 21. The lubricant placed in the well 27 will be absorbed by the leather portion 45 and will thereby keep it saturated, thereby causing it to be soft and flexible and at all times fit snugly about the shaft 3. A flexible suspending member 32 is pivotally attached to the upper part of the metal plate 50 21 and extends in an inclined direction from a vertical line drawn through the center of said plate, where it is pivotally attached to the fan casing wall 5. By this construction any vertical or horizontal variation in the 55 movement of the shaft 3 caused by the dis-alinement of said shaft due to the ordinary wear on the bearings thereof will permit the packing member to move with the shaft, the pressure of the air within the fan casing 60 at all times holding the felt portion 28 tightly against the end wall 5. By reason of the fact that I suspend the packing member upon a flexible support disposed at an angle to the vertical axis of the shaft 3 no 65 direct end thrust can be brought upon the

flexible member causing it to buckle and force the packing member away from the wall 5. It will be readily seen that by reason of the pivotal connection between the suspension member, packing member and the wall 5, the packing member is free to move in any direction at the same time keeping the felt portion 29 constantly in contact with the wall 5. Should there at any time be end play in the shaft 3 due to 70 wear in the motor or bearing 8 the leather portion 23 is free to move slightly backward and forward in line with the shaft by virtue of the frusto-conical collar formed on the plate 21. 75

Having fully described my invention what I claim as new and desire to secure by Letters Patent, is—

1. In a packing adapted to fit around a rotating shaft, a rigid member encircling 85 said shaft and spaced therefrom, a flexible member encircling said shaft in close contact therewith and secured to said rigid member, means within the said rigid member for lubricating said flexible member, 90 flexible means adapted to secure said packing against rotation with said shaft but permitting the said packing eccentric movement in any direction with said shaft. 95

2. A packing adapted to surround a rotating shaft comprising a square of metal in blank form, an integral portion depending from said square in blank form, an opening formed centrally of said square of metal, a frusto-conical flange formed about said 100 opening and adapted to encircle said rotating shaft in spaced relation thereto, a square of leather of smaller dimension than said metal square upon one side of said metal square, the corners of said metal being 105 adapted to be bent into engagement with said leather to secure said leather upon said metal; a central opening in said leather adapted to fit snugly about said shaft to form an air tight contact therewith, the 110 said lug upon said blank square being adapted to be bent upwardly to form in conjunction with the two adjacent inturned corners of said square, a reservoir for containing a lubricant for said leather, a wall 115 arranged at right angles to said shaft and intersecting said shaft, an aperture formed in said wall through which the said shaft is designed to extend, a felt member secured upon the reverse side of said metal and adapted to engage the said wall and to form an air tight joint between said wall and said metal member, a flexible strap securing said packing member upon said wall and against rotation with the said shaft but permitting 120 said packing member to move with said shaft at all times leaving the said felt member in contact with the said wall. 125

3. A packing adapted to surround a rotating shaft comprising a rectangular metal in 130

blank form, an integral portion depending from said rectangular blank form, an opening formed centrally in said blank form, a frusto-conical flange formed about said 5 opening and adapted to encircle said rotating shaft in spaced relation thereto, a sheet of fibrous material of smaller dimension

than said metal form, the corners of said metal being adapted to be bent into engagement with said fibrous material to secure 10 said fibrous material upon said metal.

In testimony that I claim the above I have hereunto subscribed my name.

ABRAHAM J. SCHANTZ.
